UNITED STATES PATENT OFFICE.

WILLIAM F. TRAUDT, OF RUTHERFORD, NEW JERSEY, ASSIGNOR TO TABER PUMP COMPANY, A CORPORATION OF NEW YORK.

APPARATUS FOR TREATING AND DELIVERING PULP.

1,089,165.

Specification of Letters Patent.

Patented Mar. 3, 1914.

Application filed February 12, 1913. Serial No. 748,052.

To all whom it may concern:

Be it known that I, WILLIAM F. TRAUDT, a citizen of the United States of America, residing at Rutherford, county of Bergen, 5 State of New Jersey, have invented certain new and useful Improvements in Apparatus for Treating and Delivering Pulp, of which the following is a specification.

My invention relates to the washing of 10 pulp and comprises apparatus by which such pulp may be thoroughly and economically washed and also, without further handling, delivered at any desired point for further treatment.

15 My invention particularly relates to the washing of pulp such as occurs in brewing processes, or of wood or other pulp which has a specific gravity not much greater than that of water. Such pulp is now washed in 20 tanks by agitating apparatus and then drawn off into filter baskets in which it is transported by hand to the filter presses.

I have invented a form of apparatus by 25 which the pulp may be both effectively washed or otherwise treated and pumped directly to the filter press in any convenient location by one pump and without manual labor.

The best form of apparatus, at present 30 known to me, embodying my invention is illustrated in the accompanying two sheets of drawings in which,

Figure 1 is a general view in side elevation of an entire apparatus. Fig. 2 is a longitudinal central vertical section of a tank and its attachments. Fig. 3 is a plan view of the same with part of the tank cover removed. Fig. 4 is an axial section of the preferred form of pump, and Fig. 5 is a cross 40 section of the pump.

Throughout the drawings like reference characters indicate like parts.

1 is a tank for containing the quantity of pulp to be treated usually having overflow 45 troughs 2, 2, at either side near the top, which are connected with the tank interior by strainers (not shown).

3, 3, are overflow pipes connected to troughs 2, 2. Preferably the tank has hinged 50 covers, two of which are shown in Fig. 3 at 4, 4. As shown, the tank 1 rests on cradles 5, 5. At one end near the bottom is the outlet extension 6 which preferably tapers as shown and connects at its smaller outer por-

tion with the inlet 12 of rotary pump 7. 55 Preferably the pump is of the centrifugal type, two radial blades 11, 11, being shown in the drawings, mounted on shaft 8. To prevent the pulp caking in the tank extension 6 and clogging the pump inlet, I extend 60 shaft 8 into the tank interior, or extension thereof, and provide it with any suitable agitating or cutting devices such as helical blades forming a pointed screw 9, shown in Figs. 2 and 4. Any suitable motor for driving 65 the pump is shown at 10.

From the pump outlet 13 a conduit 14 extends to an opening in the bottom of the tank near the other end, away from the pump, where it terminates in any suitable nozzle. 70 Preferably I use a nozzle 16 (see Figs. 2 and 3) which has a flat, flaring mouth shaped to deliver a fan like stream of liquid at a high velocity parallel to the tank bottom and away from the pump. 75

15, is a valve controlling the connection from conduit 14 to nozzle 16. The end of tank 1, against which the stream from nozzle 16 is directed is preferably joined to the tank bottom by a sweeping curve 17, tangential to the line of discharge from the nozzle. The same tank end is preferably provided with an inwardly curved deflecting plate 18, intermediate of its height. A branch conduit 19 to which access is controlled by valve 20, extends from the main conduit 14, to filter press 21, preferably terminating in a hose or other movable end section 25, controlled by valve 26. Feed water pipes 22, and 23, for hot and cold 80 water supply, connect to the tank 1 at any convenient point, preferably at the outlet extension 6 where the pulp masses are apt 85 to be densest. Valves 24, 24, control the water supply. 90

In operation tank 1 is filled with water and any proper chemicals up to the overflow level and the proper quantity of pulp dumped in. The pump is then started, valve 15 being open and valve 20 closed. The 100 pump sucks in pulp and water through inlet 12, beats the pulp with its rapidly revolving blades, and expels the pulp and water into conduit 14. From this the mixture is delivered through nozzle 16 in a flat, fan like 105 jet, under considerable pressure and velocity along the tank bottom and up the curved end 17 and against deflecting plate 18, by 95

which it is thrown out into the body of the tank with a rolling, tumbling motion which most effectively agitates and mixes it with the fluid in the tank. Any tendency of the 5 pulp to jam or cake in the tapering tank extension 6, or pump inlet 12, is counteracted by the agitating action of screw 9, and the diluting effect of the feed water delivered at that point. The surplus fluid passes 10 off through troughs 2, 2, and pipes 3, 3. When the pulp washing is completed valve 20 is opened and valve 15 shut, as are also valves 24. Continued action of the pump then draws off all the contents of tank 1 and 15 delivers them in a few minutes to one or more filter presses 21, or other receptacles.

The advantages of my invention comprise 20 the effective agitation and washing of the pulp in the course of its repeated circulation 25 through tank and pump, the beater-like action of the blades of the centrifugal pump being most effective for this purpose during its passage through the pump, and the nozzle and deflector plates producing a swirling action in the tank of like effect; the prevention of clogging in the pump inlet; and ease of transfer of the pulp to other receptacles, all by the operation of one pump.

Various changes could be made in the 30 details of the apparatus illustrated without seriously affecting its mode of operation or result so long as the principles of the inventions as above described be preserved.

Having, therefore, described my invention, I claim:

1. The combination of a tank, a centrifugal pump having its inlet connected to one end of the tank, a conduit extending from 40 the pump outlet to the other end of the tank, a filter press, a branch conduit extend-

ing from the pump outlet to said filter press, and valves controlling said conduits.

2. The combination with a tank of a centrifugal pump having its inlet connected to 45 said tank, the shaft of said pump extending into the tank and being provided with means for agitating the contents thereof.

3. The combination with a tank of a centrifugal pump having its inlet connected to 50 said tank, the shaft of said pump extending into the tank and being provided with means for agitating the contents thereof comprising helical blades.

4. The combination with a tank, a rotary 55 pump having its inlet connected to said tank near one end thereof, a conduit extending from the pump outlet to another portion of the tank, overflow connections, and a feed water pipe connected to the tank near the pump inlet.

5. The combination with a tank having a 60 tapering extension at one end near the bottom, of a rotary pump having its inlet connected to said extension, the shaft of said pump extending into said extension and being provided with means for agitating the contents thereof.

6. The combination with a tank of a centrifugal pump having its inlet connected to 70 said tank, the shaft of said pump extending into the tank and being provided with means for agitating the contents thereof, and a conduit extending from the pump outlet and opening into the tank near the other end 75 thereof.

WILLIAM F. TRAUDT.
